KEYLESS BRAKE SHOE

Joseph J. McGuire, Jessup, Pa.

Application June 13, 1940, Serial No. 340,386

4 Claims. (Cl. 188—242)

This invention relates to a brake shoe and aims to provide a novel construction which will avoid the use of a key to fasten the same to a brake head.

Considerable difficulty is experienced in connection with the attachment of brake shoes by means of a key, as the key often loosens or becomes lost as a result of the excessive vibration to which it is subjected. The key is also objectionable inasmuch as it often requires undue time in applying and removing the same.

The invention particularly aims to provide a means which will secure the shoe to the head without danger of loosening or detachment, and particularly by a means which is permanently connected to the brake shoe, and which enables the latter to be suspended centrally or above center and by the means now universally employed.

I further produce such a fastening means as will minimize the danger of loss of any parts through breakage or fracture.

The more specific objects and advantages will become apparent from a consideration of the description following taken in connection with the accompanying drawing illustrating an operative embodiment.

In said drawing:

Figure 1 is a view illustrating the invention as used in connection with the wheels of rolling stock;

Figure 2 is an enlarged elevation of a shoe and head according to the invention, being partly broken away to disclose details;

Figure 3 is a side elevation of the parts of Figure 2;

Figure 4 is a vertical section taken approximately on the plane of line 4—4 of Figure 2;

Figure 5 is a cross section taken on the line 5—5 of Figure 2, and

Figure 6 is an elevation of a brake head alone.

Referring specifically to the drawing wherein like reference characters designate like or similar parts, two wheels are shown at 10 which are conventional and representative of any wheels which may be used in connection with railway rolling stock, and which travel on rails, the wheels shown for instance being those used on a truck or bogie, two of such wheels usually appearing at each side of each bogie or truck as shown.

A brake shoe is shown at 11 which is generally arcuate as usual to conform to the periphery of the wheel 10 which it engages. The major portion of its rear surface is also arcuate for the

most part and is overlapped by four clamp lugs as at 12 which are located on opposite sides of lugs or projections 13 extending inwardly and centrally from a cross arm 13a and jointly with said projections forming T-shaped enlargements on the back of the shoe. Said lugs 12 may be made of steel or any other appropriate metal and they are preferably cast into or welded onto the shoe 11 so as to be integral therewith and bendable, pliable or resilient, so that they normally tend to spring back to their solid line positions shown in Figure 3, when forced to their dotted line position of that figure.

The shoes 11 are carried by heads such as are detailed in Figure 6 and which are generally arcuate and designated 14. Such heads 14 at opposite ends, have central notches 15 with which the lugs 13 interfit and to which the heads are applicable when the lugs 12 are in the dotted line position of Figure 3. The heads thus provide bifurcated ends which interfit with the shoes, following which, the lugs spring or are bent down to the full line position of Figure 3, overlapping and effectively securing the heads in place.

Such a connection is important, since the fastening means is not only connected to either the head or the shoe, but should any of the parts break, the size of the fracture or shape thereof is unlikely to be such that it will become detached or released in view of the interfitting feature and retention by the lugs.

The engagement of the shoe 11 and head 14 is augmented by the provision of an enlargement or rib 16 integral with the shoe and which is overlapped by ribs 17 on the heads.

The structure is suspended or positioned operatively in the brake rigging, by means of conventional links 18 which may be selectively applied in a central notch 19 of the head 14 which is closed by the rib 16 or in an upper notch 20 of such head 14, which upper notch is closed by means of a filler body 21 and which filler body 21 has a projection 22 thereon which engages in a correspondingly shaped recess 23 of the head 14 and which filler body is positioned incidental to the positioning of the head 14, prior to fastening of the latter to the shoe by the lugs 12.

Various changes may be resorted to provided they fall within the spirit and scope of the invention.

I claim as my invention:

1. Apparatus of the class described comprising a brake shoe, said shoe having projections at opposite ends thereof, retaining lugs on opposite

sides of said projections integral with the shoe, a head having bifurcated ends interfitted with said projections and retained by said lugs, said shoe having a rib, said head having a notch for engagement by a suspending link, said notch being closed by said rib, ribs on said head engaging opposite sides of the first mentioned rib, a second notch on the head engageable by a link, filler means closing the second notch located between the head and shoe, and interengaging means between the head and filler means maintaining the filler means in place by the pressure of the head.

2. Apparatus of the class described comprising a brake shoe, said shoe having T-shaped enlargements on the back thereof at opposite ends providing a cross arm and a central projection extending inwardly therefrom, retaining lugs on opposite sides of said projections integral with the cross arms and free at their inner ends, a head having bifurcated ends interfitted with said projections and overlapped and retained by said lugs.

3. Apparatus of the class described comprising a brake shoe, said shoe having T-shaped en- 25

largements on the back thereof at opposite ends providing a cross arm and a central projection extending inwardly therefrom, retaining lugs on opposite sides of said projections integral with the cross arms and free at their inner ends, a head having bifurcated ends interfitted with said projections and overlapped and retained by said lugs, said head having a notch for engagement by a suspending link, and said shoe having a rib closing said notch.

4. Apparatus of the class described comprising a brake shoe, said shoe having T-shaped enlargements on the back thereof at opposite ends providing a cross arm and a central projection extending inwardly therefrom, retaining lugs on opposite sides of said projections integral with the cross arms and free at their inner ends, a head having bifurcated ends interfitted with said projections and overlapped and retained by said lugs, said head having a notch for engagement by a suspending link, said shoe having a rib closing said notch, and ribs on said head engaging opposite sides of the first mentioned rib.

JOSEPH J. McGUIRE.
